UNITED STATES PATENT OFFICE.

ROBERT NAGLO, OF WIESBADEN, GERMANY.

PROJECTILE.

No. 911,430.

Specification of Letters Patent.

Patented Feb. 2, 1909.

Application filed May 18, 1908. Serial No. 433,520.

To all whom it may concern:

Be it known that I, ROBERT NAGLO, mayor, a subject of the King of Prussia, and residing at No. 72 Kaiser Friedrichring, Wiesbaden, Germany, have invented certain new and useful Improvements in Projectiles, of which the following is a specification.

The present invention relates to so called double-ogival projectiles. Its new feature 10 consists in the front-point gradually thickening itself to the biggest sectional area from which area it tapers without intercalation of a long cylindrical guide-part, so that the tail-point beginning from the said biggest sectional area or from the end of the 15 short guide-part constitutes at least one half of the total length. In this way the center of gravity by the very form of the projectile moves relatively far to its head whereby a 20 long tail steering point is obtained, which centers the projectile in the barrel, so that it may be fired off without bottom guide and gives the projectile the necessary stability in flight.

25 The new projectile may be made wholly out of hardened steel and is coated on its biggest sectional area with copper or the like or be provided for the purpose of easier production on its whole fore-part with a 30 copper-cap. The purpose of this is to provide the projectile with an envelop of softer material than the steel body, so that said envelop may be pressed into the groove of the rifle barrel to give the projectile the 35 necessary guidance.

Figure 1 is an elevation of the projectile; and Fig. 2 a longitudinal sectional view thereof.

For the purpose of illustrating the invention 40 the new projectile is schematically represented in the accompanying drawing. The fore-point or head *a* turns into a thickened portion *b*, which contains the largest sectional area and has to care for tightening 45 the projectile in the barrel or grooves. Thus the projectile gradually and centrally glides into the grooves whereby the depth of the grooves is filled up with the smallest amount 50 of friction imaginable. From the largest sectional area the projectile tapers back- 55 wards to the point *c* which being outwardly closed all around permits the air when the projectile is in flight to glide along the walls without resistance and prevents the project- ile from forming a vacuum behind itself. This peculiar shape of the rear-portion or

tail of the projectile which may be termed a steering point in connection with the fact that the center of gravity moves beyond the middle of the length to about the line *a*—*a* 60 helps on the one hand to center the projectile in the barrel and on the other hand to steer it during flight, so that even projectiles being more than four fold the caliber may be used without increasing the twist. The 65 pointed head and tail of the projectiles may be curved either convexly or concavely upon different angles of the points. As shown in the drawings the projectile is convex in contour from end to end and forms a line of 70 continuously changing curvature. The copper-cap may be given in front under certain circumstances a larger thickness as indicated in Fig. 2 so that the center of gravity owing to the difference between the specific weights 75 of the metals moves towards the fore-part of the projectile whereby the tail point consequently may be proportioned a little shorter than before.

Claims—

1. A projectile formed circular in cross-section at all points throughout its length and provided with a forwardly tapering pointed head, said head terminating at the point of greatest cross-sectional area and the remainder of the projectile tapering from said point of greatest cross-sectional area to its rear end on a line of continuously changing curvature, the rear end of the projectile being pointed, the point of greatest cross-sectional 90 area being forward of the middle of the projectile, whereby the center of gravity will be forward of the middle and the tapering rear part of the projectile will be greater in length than the tapering forward part thereof. 95

2. A double ogival projectile formed with a front portion gradually thickening to the greatest cross-sectional area from which point it tapers rearwardly without intercalation to form a long guide part, the projectile 100 being circular in cross-section at all points throughout its length, the point of greatest cross-sectional area being forward of the middle thereof, whereby the center of gravity of the projectile will be forward of its 105 middle.

3. A projectile pointed at both ends and circular in cross-section at all points throughout its length and formed with a gradually enlarging portion which extends to the point 110 of greatest cross-sectional area, the rear portion tapering from said point of greatest

cross-sectional area to the rear end of a line of continuously changing curvature, the contour of the projectile being convex from end to end and the point of greatest cross-sectional area being forward of its middle.

4. A projectile formed circular in cross-section at all points throughout its length and provided with a forwardly tapering pointed head, said head terminating at the point of greatest cross-sectional area and the remainder of the projectile tapering from said point of greatest cross-sectional area to its rear end on a line of continuously changing curvature; the rear end of the projectile being pointed, the point of greatest cross-sectional area being forward of the middle of the projectile, whereby the center of gravity will be forward of the middle and the tapering rear part of the projectile will be greater in length than the tapering forward part thereof, and a soft metal cap covering the forward portion of the projectile and extending over the part of greatest cross-sectional area.
5. A double ogival projectile formed with a front portion gradually thickening to the greatest cross-sectional area from which point it tapers rearwardly without intercalation

to form a long guide part, the projectile being circular in cross-section at all points throughout its length, and a soft metal coating covering the portion of greatest cross-sectional area.

6. A projectile pointed at both ends and circular in cross-section at all points throughout its length and formed with a gradually enlarging head portion which extends to the point of greatest cross-sectional area, the rear portion tapering from said point of greatest cross-sectional area to the rear end on a line of continuously changing curvature, the contour of the projectile being convex from end to end and the point of greatest cross-sectional area being forward of its middle, and a soft metal cap covering the forward portion of the projectile and extending over the portion of greatest cross-sectional area, said cap extending forward of the front end of the projectile.

In testimony whereof I have signed my name to this specification in the presence of two subscribing witnesses.

ROBERT NAGLO.
